EVAPORATOR FOR USE IN REFRIGERATION
DEVICES

Lewis M. Crosley and Roland H. Money, Cincinnati, Ohio, assignors to The Crosley Corporation, a corporation of Ohio

Application July 23, 1936, Serial No. 92,172

8 Claims. (CL 62—126)

Our invention relates to evaporators for use principally in domestic refrigerators where the evaporators are employed for the reception of ice trays in the production of ice cubes for domestic use. In general, the type of our evaporator is one formed of sheets of metal united together and shaped so as to define refrigerant passages.

It is one of our objects to provide an evaporator in which the refrigerant instead of flowing from one header to another through a series of parallel passageways, in one direction, flows through a sinuous passageway throughout the evaporator in one direction, and then back again in the opposite direction.

15 It is an object of our invention to provide an evaporator structure which has sufficient strength for domestic use, and which consists externally of a soft metal such as brass, which is relatively non-corrodible, and does not require extensive 20 surface treatment after it is formed up or prior thereto. To this end, in one modification we incorporate a steel sheet as a diaphragm or passageway defining element between two outer sheets of the brass, so arranging it, however, that 25 the steel sheet is not exposed externally of the device, but terminates short of the welded together edges of the brass sheets.

In another modification of our invention we provide a soft metal diaphragm, such as a diaphragm of copper, in a brazed construction hereinafter to be described.

We have illustrated a preferred form of our structure in the appended drawings, and will describe the same in detail, it being understood 35 that the novelty inherent in the structure is set forth in the appended claims, to which reference is hereby made.

In the drawings:

Fig. 1 is a plan view of the evaporator prior 40 to bending.

Fig. 2 is a section on the line 2—2 of Fig. 1.

Fig. 3 is an edgewise elevation of the device shown in Fig. 1.

Fig. 4 is an elevation taken from the front of 45 the completed evaporator.

Fig. 5 is a side elevation of the said device as shown in Fig. 4.

Fig. 6 is a section on the line 6—6 of Fig. 5.

Fig. 7 is a detail plan view taken of the portion indicated at 7—7 on Fig. 4.

In forming the evaporator device, sheets of brass or other suitable soft, non-corrosive metal 50 1 and 2, are pressed or otherwise formed so as to present two semi-circular parts 3 and 4, which 55 when united together will form a cylindrical

header 5. The plate 1 is formed with an aperture for an entrance fitting 6 for refrigerant gases, from which aperture a sinuous corrugation 7 extends, this corrugation passing back and forth with a plurality of bends, then extending straight 5 5 as indicated at 7a, and then again formed into loops beginning at 7b and terminating at 7c.

Referring to Fig. 1, the evaporator will be subsequently bent at right angles along dotted lines marked A, B and C, and the straight portions 7a 10 of the corrugation in plate 1 traverse the section A to B. The other plate 2 of soft metal or brass, has a sinuous passage which extends into the half portion 4 of the header, and beginning at 8 15 describes a sinuous path of a series of loops terminating at a point 8a, thence extending straight to the point 8b.

The steel sheet 9 need not be corrugated and is of a size such that its edge 9a falls short of the uncorrugated edges of the two soft metal plates 20 when the steel plate is placed between the two soft metal plates, with the edges of the two soft metal plates coinciding entirely around the assembly. As so assembled, continuous welds 10 25 can be made extending in from the edges of the soft metal plates on both sides of the structure, where not interfered with by the loops of the corrugations. Also spot welds as at 11 may be made uniting the two outer plates to the middle plate or diaphragm. Also the coinciding edges 30 all the way around the structure are welded or brazed together, and if desired, a facing strip 12 may be mounted over what will be the front edge of the structure.

As so constructed the device is ready for bending into final form, which will result in the forming of a vertical wall 12, the bottom wall 13, the side wall 14 and a top wall 15. Due to the arrangement of the corrugations, the portion 7a of the corrugations 7, and the portion between 8a 40 and 8b of the corrugation 8, will be at the back end of the finished structure, leaving flat tray supporting shelves at 16 and 17. A mounting bracket 18 may be secured to the one side of the device with a mounting plate 19, for an electric 45 light switch, the bulb being housed in the portion 20 of this bracket. In order to provide for tray lifting devices, consisting of a loop of wire 21 operated by handle 22, held in a plate 23, the loops of the corrugations in the two brass plates 50 will be made shorter as indicated. In order to accommodate the mounting plate 23, the steel plate 9 is cut away as at 9b, thus permitting the mounting plates to be pressed in flush with the 55 surface of the tray supporting shelves of the com-

pleted device. The diaphragm or steel plate will have a hole $9c$ therein which permits the sinuous passageway 7 to communicate with the sinuous passageway 8 at the point $8b$. Otherwise the 5 diaphragm serves to define, with the corrugations in the tray plates, semi-circular passageways. As a result, in the finished device, the refrigerant enters at 6 , passes down the side 12 , on the inside of the device, along the back of the 10 shelf 16 , up the side 14 and along the bottom of the shelf 17 . The refrigerant then enters passageway 8 , flows along the back of the shelf 17 , thence through a sinuous path along the side 14 , the bottom 13 , and up on the outside of the wall 15 12 , from which it enters the head.

It will be apparent that this evaporator will be inexpensive to form, require no elaborate surface treatment, make it unnecessary to provide two headers, will provide for refrigerated walls as well 20 as both shelves of the evaporator, and will be amply strong to withstand the necessary service.

A second modification of our invention has to do both with the use of lighter metal and with the avoidance of any possibility of buckling during 25 the bending step which may arise from the use of a stiff or hard metal diaphragm member. Evaporators for domestic refrigerators have to be made to withstand considerable internal pressure especially when the machine is idle or during 30 periods of shipment. The tensile strength of brass or other soft metals, that is, metals in fairly light gauges, is amply sufficient to sustain these pressures. Thus where a plate such as the plate 1 or 2 is embossed to form a passageway no difficulty is experienced. Where, however, a flat portion of one plate lies opposite an embossed portion of another plate, as for example, between the dotted lines A and B in Fig. 1, and where the flat portion of the plate is subjected to internal pressure, there may be a slight distortion of the plate 40 between the lines of welding, producing a slightly irregular surface and an unsightly appearance. In the modification of our invention which we are now describing we make use of the diaphragm 45 as a means for reenforcing a flat or unembossed portion of a plate lying thereagainst. In an exemplary manufacture of this type of evaporator we may employ for example, as the plates 1 and 2 , plates of brass of $.025$ inch in thickness, and we 50 may employ as the diaphragm the plate indicated in the figures at 9 , that is a plate of copper, say of $.020$ inch in thickness. It will be understood that these dimensions are exemplary only and are not limiting. The plates (or at least the diaphragm 55 plate) having been suitably coated with a flux after cleaning, are assembled as has been indicated, and then the plates are brazed together throughout their contacting surfaces, preferably by the now well-known hydrogen brazing method.

60 The plates in their flat portions are thus integrally joined. In the embossed portions the $.025$ brass will have sufficient tensile strength to give an adequate margin of safety. Over flat portions at least one plate will be joined to the diaphragm 65 plate, giving an effective metal thickness or gauge of $.045$ at least, this being amply sufficient to withstand any tendency for the plates to distort under the internal pressures to which the evaporator may be subjected.

70 It will be understood that in forming this type of evaporator it will be necessary to choose both for the outer plates 1 and 2 and for the diaphragm member 9 , metals which are capable of being brazed together. The use of a softer metal in 75 the diaphragm member makes the bending up of

the evaporator structure into the forms shown in Figs. 4 and 6 somewhat easier in that there is less tendency toward buckling.

In the manufacture of either of the modifications of the evaporator described herein, it will be desirable to roughen portions at least of the surfaces of the diaphragm member or inside portions of the surfaces of the other plates so as to promote boiling of the liquefied refrigerant. It will also be understood to be within the scope 10 of our invention, where embossed passageways cross the lines along which the evaporator is to be joined, to make the embossed passageways at such points larger or different in cross section so as to compensate for any swaging or flattening 15 of the passageways which might occur during bending.

Having thus described our invention, what we claim as new and desire to secure by Letters Patent is:

20 1. An evaporator structure comprising a pair of plates made of soft relatively non-oxidizable metal, and an interposed diaphragm formed of iron or steel, each plate having corrugations therein to form in cooperation with the interposed diaphragm a refrigerant passageway, said diaphragm terminating short of the edges of said plates, the edges of the plates being welded together, said diaphragm being provided with an opening connecting the corresponding ends of 30 said passageways.

25 2. An evaporator structure comprising a pair of plates made of soft relatively non-oxidizable metal, and an interposed diaphragm formed of iron or steel, each plate having corrugations 35 therein to form in cooperation with the interposed diaphragm a refrigerant passageway, said diaphragm terminating short of the edges of said plates, the edges of the plates being welded together, said diaphragm being provided with an 40 opening connecting the corresponding ends of said passageways, said plates at one end being formed into a header for the return flow passageway.

45 3. In an evaporator assembly, a pair of plates welded together at the edges and spread at one end of the assembly to form a header, a diaphragm plate secured between the two plates, a sinuous bead formed in each outer plate to form in cooperation with the diaphragm plate a passageway for refrigerant, said latter plate arranged to close the passageways from each other, said diaphragm being provided with an opening at said end to provide a port between said passageways.

50 4. In an evaporator assembly, a pair of plates welded together at the edges and spread at one end of the assembly to form a header, a diaphragm plate secured between the two plates, a sinuous bead formed in each outer plate to form 55 in cooperation with the diaphragm plate a passageway for refrigerant, said latter plate arranged to close the passageways from each other, said diaphragm being provided with an opening at said end to provide a port between said passageways, said plates and diaphragm bent to form a rectangular open end structure, thus presenting a lower and an upper ice tray shelf.

60 5. In an evaporator assembly, a pair of plates welded together at the edges and spread at one end of the assembly to form a header, a diaphragm plate secured between the two plates, a sinuous bead formed in each outer plate to form 65 in cooperation with the diaphragm plate a passageway for refrigerant, said latter plate ar- 70 75

ranged to close the passageways from each other, said diaphragm being provided with an opening at said end to provide a port between said passageways; said plates and diaphragm bent to form 5 a rectangular open end structure, presenting a lower and an upper ice tray shelf portion, the sinuous bead in each shelf portion being so arranged therein so that said shelf portion presents a substantially flat surface for supporting an ice 10 tray.

6. In a refrigerator evaporator, a pair of outer plates and a diaphragm plate therebetween, said outer plates being embossed to form passageways completed by said diaphragm member, certain embossed portions in one plate lying opposite flat portions in the other plate, and said diaphragm plate being joined to said flat portions of said other plate whereby to stiffen said flat 15 portions.

20 7. In an evaporator, a pair of outer plates and

a diaphragm plate therebetween, said outer plates being welded together about the edges thereof and being embossed to form passageways completed by said diaphragm plate, and entrance and exit means for refrigerant, at least one plate surface located interiorly of said evaporator being roughened to promote the boiling of liquid refrigerant therein said diaphragm plate terminating short of the edge welded portions of said outer plates. 10

8. An evaporator structure comprising a pair of plates and a diaphragm interposed between the same, said plates having corrugations therein to form passageways in cooperation with the diaphragm, said diaphragm terminating short of the 15 edges of said plates, the edges of the plates being welded together, and said diaphragm roughened to promote boiling of the refrigerant.
